CLAIM

An ornamental design for an outsole, as shown and described.

DESCRIPTION

FIG. 1 is a perspective view of an ornamental design for an outsole according to the invention;

FIG. 2 is a partial, bottom view of an ornamental design for an outsole according to the invention;

FIG. 3 is a bottom view of another embodiment of an ornamental design for an outsole according to the invention, the embodiment shown having three elongated grooves in the forefoot portion of the outsole instead of twenty individual triangular grooves shown in FIG. 2 but being otherwise identical;

FIG. 4 is a side view of an ornamental design for an outsole according to the invention;

FIG. 5 is a reverse side view of an ornamental design for an outsole according to the invention;

FIG. 6 is a top view of an ornamental design for an outsole according to the invention;

FIG. 7 is a front view of an ornamental design for an outsole according to the invention; and,

FIG. 8 is a rear view of an ornamental design for an outsole according to the invention.

The broken lines depict the boundaries of the claimed design, and areas they enclose form no part of the claimed design.

1 Claim, 4 Drawing Sheets
